VAPOR GENERATOR

Martin Frisch, New York, N. Y., assignor to Foster Wheeler Corporation, New York, N. Y., a corporation of New York

Application November 17, 1941, Serial No. 419,388

6 Claims. (Cl. 122—478)

This invention relates to vapor generators and more particularly pertains to apparatus for generating and superheating steam.

The invention provides a multiple furnace superheating steam generator of novel and compact arrangement with which superheat control at all loads on the generator is obtained.

The features and advantages which characterize the invention will be understood from the following description considered in connection with the accompanying drawings forming a part thereof, and in which:

Fig. 1 is a vertical sectional view of a steam generator embodying the invention;

Fig. 2 is a horizontal sectional view taken on line 2—2 of Fig. 1;

Fig. 3 is a horizontal sectional view taken on line 3—3 of Fig. 1;

Fig. 4 is a horizontal sectional view taken on line 4—4 of Fig. 1, and

Fig. 5 is a horizontal sectional view taken on line 5—5 of Fig. 1.

Like characters of reference refer to the same parts throughout the several views.

Referring to the drawings the steam generator illustrated has substantially vertical refractory side walls 11 and 12, a rear side wall 13, a front side wall, not shown, an end wall having roof portions 14 and 15 and an end wall having furnace bottom portions 36 and 37. Adjacent one side of the roof portion 14 is a steam and water drum 16. Connected to this drum is a bank of substantially vertical steam generating tubes 17 which extend downwardly adjacent and parallel to the side wall 11 and at their lower ends are connected to a drum 18. The tubes are disposed in a gas pass 19 which is defined by the wall 11 on one side of the tube bank and a vertical baffle wall 20 on the other side. This pass 19 communicates at its upper end with an outlet flue 21. Spaced inwardly a short distance from the vertical baffle 20 is a vertical partition wall 22.

Adjacent the opposite side of the setting is a corresponding vertical partition wall 23 which is disposed inwardly of the side wall 12 and forms therewith a vertical gas pass 24 which communicates at its upper end with a flue gas outlet 25. Within the setting and between the partition walls 22 and 23 are two separate furnaces 26 and 27 arranged to operate in parallel, and which are fired, respectively, by the fuel burner 28 disposed in the roof portion 14, and by the fuel burner 29 disposed in the roof portion 15. A vertical partition wall 30 separates the two furnaces and forms the inner boundary thereof, while the par-

tition walls 22 and 23 respectively define the outer boundaries of the furnaces. The furnace side of the wall 22 is lined by water wall tubes 31 which extend from the drum 16 to a lower header 32. Opposite sides of the partition 30 are lined, respectively, by water wall tubes 33 and 34 which extend from the drum 16 across the inner surface of the roof portion 14 and are connected at their lower ends to a header 35. The front and rear walls of the furnaces are similarly lined with water wall tubes, although they are not shown, and the several tube groups described and referred to are suitably connected into the circulatory system of the unit. Inwardly inclined furnace bottom wall portions 36 and 37, the upper ends of which are spaced from the lower ends of the partition walls 22 and 23 respectively, provide the furnaces with hopper bottoms. A soot hopper 38 is disposed directly below the gas pass 19 or heating chamber 19, while a similar soot hopper 39 is disposed directly below the gas pass or heating chamber 24. The side walls 11 and 12 of the setting are respectively provided with a plurality of lancing doors 40 and 41.

In the form of the invention illustrated, a combination radiant and convection superheater is utilized and is so arranged and disposed that it is exposed to the products of combustion produced in one furnace only, i. e., the furnace 27, which may be referred to as the superheater furnace. The furnace side of the partition wall 23, is lined with vertical radiant heat superheater tubes 42 and 43 which are arranged as shown in Fig. 3, and which form a continuous panel or section of radiant heat absorbing surface except at 46 where the tubes are spread apart, as shown more particularly in Fig. 4, to form a furnace gas outlet passage between the bottom of the partition 23 and the top of the inclined wall 37. The tubes 42 which are connected to the steam space of the drum 16 in two spaced longitudinal rows as shown in Fig. 5, conduct the steam across the furnace roof portion 15 and downwardly in one pass to a lower header 44 from which the steam flows upwardly in one pass through the tubes 43 to a point adjacent the top of the partition wall 23 where they pass through the partition and are formed into a plurality of return bend loops of a convection superheater section 45 which is vertically disposed in the gas pass 24 through which gases flow from the furnace 27 to the outlet flue 25. The tubes 43 of the radiant heat superheater section and the tubes 45 of the convection section, which are arranged for series flow of steam therethrough, are continuous with

each other as shown, and no intermediate header connections are required between the two sections. Superheated steam flows from the tubes of the convection section to a superheater outlet header 47 which is fixed in position adjacent the bottom of the setting and from which the superheated steam is conducted to a point of use. The outlet end portions of the convection superheater tubes are formed into a partial loop to provide for expansion of the tubes.

In operation, the gases produced in the furnace 26, which may be called the saturated steam furnace, flow downwardly through the furnace and through gas outlet passage 48 which is similar to the gas outlet passage 46, and upwardly over the steam generating tubes 17 to the outlet flue 21. Saturated steam is conducted from the upper drum 16 and flows downwardly through the tubes 42 and upwardly through the tubes 43 mainly in radiant heat exchange relationship with the gases produced in superheater furnace 27. From this radiant heat absorbing section of the superheater, the steam flows through the loop elements of the convection superheater section 45 in convection heat exchange relationship with the gases flowing from the furnace 27 through the gas pass 24 to the flue outlet 25. The quantity of steam produced will be determined largely by the rate at which the furnace 26 is fired, although some steam will be generated in water walls of the furnace 27. Inasmuch as the gases produced in the saturated steam furnace 26 do not flow in heat exchange relationship with the superheater, the degree to which the steam is superheated will be determined by the degree to which the superheater furnace 27 is fired. Furnace 27 may be fired to obtain the superheat temperature desired at any load on the generator, or it may be fired to obtain and to maintain a substantially constant degree of superheat at all loads on the generator. The superheating characteristics of the combination radiant heat and convection superheater employed, contribute to the maintenance of a constant superheat temperature.

With this arrangement, since the superheater sections are entirely shielded from the gases leaving one of the furnaces, the steam generator may be started up by firing that furnace only, thus eliminating any necessity for flooding the superheater during starting up periods. This considerably shortens the time ordinarily required to bring the unit onto the line. Also if a feed water heater were out of service, a constant steam temperature can be maintained without the use of a by-pass or any other means of superheat control except for the differential firing provided.

The elimination of intermediate header connections between the radiant and convection sections of the superheater, simplifies and reduces the cost of construction of the superheater and reduces the pressure drop, although intermediate headers may be employed if desired. The relatively large amount of furnace cooling surface possible with the multiple furnace arrangement, and the vertically downward firing of the fuel burners, results in low temperatures in the ash rejecting zones of the furnaces and thus tends to insure dry ash removal.

With the bank of steam generating tubes and the heating surface of the convection superheater section disposed adjacent the side walls of the setting, heat losses by radiation are reduced to a minimum, and the surface of these two tube groups are readily accessible to cleaning through

the lancing doors 40 and 41. This is particularly desirable when certain types of fuel, such as high volatile coals are employed, because the ash of such fuel frequently tends to become soft and to adhere to the surface of the tubes in undesirable quantities at relatively low temperatures.

It will be understood that changes may be made in the form, location and relative arrangement of the several parts of the steam generator disclosed herein without departing from the principles of the invention. Consequently, the invention is not to be limited excepting by the scope of the appended claims.

What is claimed is:

15. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said firing means are disposed, each of said firing means being arranged to direct its gases of combustion in a substantially vertical path of flow toward the gas outlet opening of the furnace with which it is associated, means forming a gas passage adjacent an outer wall of each furnace and 20 extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.
20. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said firing means are disposed, each of said firing 25 means being arranged to direct its gases of combustion in a substantially vertical path of flow toward the gas outlet opening of the furnace with which it is associated, means forming a gas passage adjacent an outer wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.
30. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said firing means are disposed, each of said firing 35 means being arranged to direct its gases of combustion in a substantially vertical path of flow toward the gas outlet opening of the furnace with which it is associated, means forming a gas passage adjacent an outer wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.
40. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said firing means are disposed, each of said firing 45 means being arranged to direct its gases of combustion in a substantially vertical path of flow toward the gas outlet opening of the furnace with which it is associated, means forming a gas passage adjacent an outer wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.
50. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said firing means are disposed, each of said firing 55 means being arranged to direct its gases of combustion in a substantially vertical path of flow toward the gas outlet opening of the furnace with which it is associated, means forming a gas passage adjacent an outer wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.
60. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said firing means are disposed, each of said firing 65 means being arranged to direct its gases of combustion in a substantially vertical path of flow toward the gas outlet opening of the furnace with which it is associated, means forming a gas passage adjacent an outer wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.
70. Vapor generating apparatus comprising a setting, means providing two separate furnaces in the setting separated by an imperforate wall, means for firing each furnace disposed at one end of the setting, the setting having a gas outlet for each furnace, each furnace having a gas outlet opening in a side wall thereof other than the wall separating the furnaces and adjacent the end of the setting opposite the end at which said

firing means are disposed, each of said firing means being arranged to direct its gases of combustion in a substantially vertical path of flow toward the gas outlet opening of the furnace with which it is associated, means forming a gas passage adjacent an outer wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and a superheater having a part within the other gas passage and another part in the furnace adjacent said passage and along a wall of said furnace.

4. Vapor generating apparatus comprising a setting, means providing two separate furnaces in the setting separated by an imperforate wall, burner means for firing each furnace disposed at the top thereof, the setting having a gas outlet at the top thereof for each furnace, each furnace having a gas outlet opening at the bottom of a side wall thereof other than the wall separating the furnaces, each of the burners being arranged to direct its gases of combustion in a substantially vertical path of flow toward the gas outlet opening of the furnace with which it is associated, means forming a gas passage adjacent said side wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating surface in one gas passage, and vapor superheating surface in the other gas passage.

5. Vapor generating apparatus comprising a setting, means providing two separate furnaces in the setting separated by an imperforate wall, burner means for firing each furnace disposed at the top thereof, the setting having a gas outlet at the top thereof for each furnace, each furnace having a gas outlet opening at the bottom of a side wall thereof other than the wall separating the furnaces, each of the burners being arranged to direct its gases of combustion in a substantially vertical path of flow toward the gas outlet opening of the furnace with which it is associated, means forming a gas passage adjacent

said side wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating tubes on the furnace side of said side wall other than the wall separating the furnaces, said tubes extending over the gas outlet opening and spaced apart at said opening to permit flow of gases into the passage, vapor generating surface in one gas passage, and a superheater within the setting having a part within the other gas passage and another part in the furnace adjacent said passage and along a wall of said furnace.

6. Vapor generating apparatus comprising a setting, means providing two separate furnaces in the setting separated by an imperforate wall, burner means for firing each furnace disposed at the top thereof, the setting having a gas outlet at the top thereof for each furnace, each furnace having a gas outlet opening at the bottom of a side wall thereof other than the wall separating the furnaces, each of the burners being arranged to direct its gases of combustion in a substantially vertical path of flow toward the gas outlet opening of the furnace with which it is associated, means forming a gas passage adjacent said side wall of each furnace and extending along that furnace, the gas passages being oppositely disposed with the furnaces therebetween, each gas passage being in communication with the gas outlet of the setting for the furnace adjacent thereto and the gas outlet opening for said furnace and having one dimension which is less than the corresponding dimension of the adjacent furnace, vapor generating tubes on the furnace side of said side wall other than the wall separating the furnaces, the tubes on the one side wall of one of the furnaces being spaced apart, said tubes extending over the gas outlet opening and spaced apart at said opening to permit flow of gases into the passage, a superheater in the setting having tubes disposed in the spaces between the spaced vapor generating tubes on said side wall of said one furnace and extending within the passage adjacent the said side wall thereof, and vapor generating surface in the setting in the passage receiving gases from the other furnace.

MARTIN FRISCH.
